Patented July 19, 1921.

UNITED STATES PATENT OFFICE.

HERMAN E. GOTHLBERG, OF ROSELLE PARK, NEW JERSEY.

MAT.

1,384,891.

Specification of Letters Patent. Patented July 19, 1921.

Application filed February 12, 1919. Serial No. 276,642.

To all whom it may concern:

Be it known that I, HERMAN E. GOTHLBERG, a citizen of the United States, and a resident of Roselle Park, county of Union, 5 State of New Jersey, have invented certain new and useful Improvements in Mats, of which the following is a specification.

The present invention relates to mats, and while the same is capable of more or less general use, the present embodiment is adapted especially for use upon the running boards of automobiles, carriages or the like. An object of the invention is to provide a mat having a cleansing surface adapted to remove 10 dirt or debris from the shoes, and in which the dirt or debris will be precipitated from the mat so that the same will at all times be maintained clean. Another object is to provide in connection with such a mat, scrapers 15 for removing the dirt from the shoes and a frictional tread surface for the purpose of preventing slipping. It is further proposed to provide a mat which may be set into the running board or other supporting surface, 20 and forming in effect a part thereof, and in which the exposed surface subject to wear may be removed and replaced when desired to the end that the mat may be always maintained in perfect condition at a relatively 25 small cost, while at the same time, constituting a substantially permanent fixture of the structure carrying the same as for instance, 30 an automobile.

With these and other objects in view, embodiments of my invention are shown in the accompanying drawings, and these embodiments will be hereinafter more fully described with reference thereto and the invention will be finally pointed out in the appended claims.

In the drawings:

Figure 1 is a plan view showing one embodiment of my invention set in the running board of an automobile;

Fig. 2 is a plan view of the mat removed from the running board and with the cleansing members and friction tread members removed;

Fig. 3 is a bottom plan view of the mat, the cleansing members and friction tread members being inserted;

Figs. 4, 5 and 6 are longitudinal sectional views taken respectively along the lines 4—4, 5—5 and 6—6 of Fig. 1;

Fig. 7 is an enlarged transverse sectional view taken along the line 7—7 of Fig. 1;

Fig. 8 is a perspective view of one of the friction tread members;

Fig. 9 is a perspective view of one of the cleansing brush members;

Fig. 10 is a longitudinal sectional view of a modified form of brush member with parts broken away;

Fig. 11 is a transverse sectional view thereof;

Fig. 12 is a longitudinal sectional view of a further modified form of a brush member with parts broken away; and

Fig. 13 is a transverse sectional view thereof.

Similar reference characters indicate corresponding parts throughout the several figures of the drawings.

Referring to the drawings and more particularly to Figs. 1 to 9 thereof, the running board 20 of the automobile or any other suitable supporting structure is provided with a rectangular opening 21 in which the mat is set, the mat comprising an angular frame 22, the upper lateral flange of which 23 engages the upper surface of the running board and is secured thereto by means of screws 23. The frame is preferably formed of cast metal and extending between the ends of the same and preferably formed integrally therewith, there are provided a plurality of spaced channel members 24 and alternating therewith and within the spaces between the said channels, there are provided a plurality of portions 25 having 75 sockets 25^a. The sockets 25^a in the portions or members 25 are spaced from the channel members 24 as clearly shown in Fig. 7. The upper surfaces of the channel members and the portions 25 are substantially in the same 80 plane and are below the upper surface of the flange 22 of the frame.

The outermost channel members 24 are spaced from the adjacent sides of the frame 22 and within the space thus formed, and 85 spaced from the channel members and the frame there are provided scraper bars 26, the ends of which extend to and are preferably integral with the ends of the frame. The upper surfaces of these scraper bars 90 are substantially flush with the upper surface of the frame but at their end portions, they are cut out as at 28 so that the said cut-outs are in substantially the same plane 95 as the upper surfaces of the channel members and the socket portions.

The bases of the channel members are

provided with elongated openings 29 which materially lighten the weight of the mat and at the same time form an outlet for water or dirt that may accumulate in the channels as will hereinafter appear.

Within the channel members there are disposed removable friction tread members in the form of elongated strips 30, formed of rubber or canvas, or other suitable yieldable material providing a frictional gripping surface. The upper surface 31 of the said strips is provided with longitudinal corrugations and the ends of the strips are tongued as at 32 and 33, these tongues when the strips are set in the channels, having their upper surfaces substantially flush with the upper surfaces of the channel members and the socket portions while the frictional tread surface 31 projects above the same.

Elongated brush members 34, backs 35 of which are formed of wood or other suitable slightly flexible material, are placed between the channel members, the ends of said brush members being disposed within the sockets of the socket portions 25 and retaining bars 36 and 37 are placed over the ends of said brush members and the frictional tread members 30, the same being secured in place by means of screws 38, which extend through the ends of the frictional tread members, thereby preventing longitudinal displacement of the same, and engage the bases of the channel members 24. The upper surfaces of the brush members extend above the frictional tread members and also preferably above the surface of the frame, thereby providing a frictional contact surface.

The upper surfaces of the brush members, as above stated, project above the frictional contact surface and as the foot treads thereon, the resilient back permits a certain amount of deflection of these members so that they engage the foot under pressure, which action together with the movement of the foot across the brushes results in a thorough cleansing of the same, the debris removed, falls through the spaces between the brushes to the road, or if desired, a suitable receptacle may be placed below the mat to receive the debris. When the brushes and the frictional gripping members become worn to such an extent that they do not function properly, they may be readily replaced by removing the retaining bars 36 and 37 and inserting new brushes and frictional gripping members in the supports therefor. The openings 29 in the bases of the channel supports 24 prevent the accumulation of water or debris within the channels.

In Figs. 10 and 11, I have illustrated a modified form of brush member which consists of a channel bar 39 closed at its ends as at 40, and having inserted therein a brush of the circular type, the bristles 41 being secured by twisted wires 42, the said bristles

being bent upwardly so that they project through the openings of the channel as indicated in Fig. 11.

In Fig. 12 and 13, I have shown a further modified form consisting of a cylindrical brush 43, disposed in a channel bar 44, the wire ends 45 and 46 of the brush being journaled in the ends 47 and 48 of the channel. This brush may be clamped at its ends in such manner that it will be held stationary so that as the surface becomes worn, new brush surfaces may be brought into place or else the same may be loosely mounted to revolve when engaged by the surface of the shoe or other surface to be cleansed. An opening 49 is provided in the bottom of the channel to permit of the precipitation of debris collected therein. The brushes shown in Figs. 10 and 13, it will be understood, are inserted in the frame in a similar manner to the brushes 34.

I have illustrated and described preferred and satisfactory embodiments of my invention, but it is obvious that changes may be made therein within the spirit and scope thereof as defined in the appended claims.

I claim:

1. In a mat, a supporting frame, frictional gripping means supported in said frame in spaced relation, and brush members supported in the spaces between said frictional gripping means and spaced from said frictional gripping means, debris from said frictional gripping means and said brush members adapted to be precipitated through the spaces therebetween.

2. In a mat, a supporting frame, a plurality of channel supports disposed within said frame in spaced relation, supporting socket means adjacent the ends of said channel supports and within the spaces therebetween, resilient frictional gripping means supported within said channel supports, and brush members disposed in spaced relation between said resilient frictional gripping means, and having their ends supported in said socket means.

3. In a mat, a supporting frame, gripping means supported in said frame in spaced relation, and brush members disposed within the spaces between said gripping means and spaced from said gripping means, the upper surface of said brush members being above the upper surface of said gripping means.

4. In a mat, friction gripping means held in spaced-apart relation, and brushing means alternating with the gripping means and resiliently supported.

5. In a mat, friction gripping means held in spaced-apart relation, brushing means alternating with the gripping means and spaced therefrom, said brushing means extending above the gripping means and being resiliently supported and adapted to be depressed and put under tension.

6. In a mat, friction gripping means, brushing means alternating therewith, said gripping and brushing means being separated by spaces through which debris may fall, and scraping means mounted in conjunction with the gripping and brushing means.
7. In a mat, a frame of open construction, supports extending across the same, friction gripping means removably held on said supports, and resiliently supported brushes also extending across the frame and spaced from the supports.
8. In a mat, in combination with a support
- having an opening therein, an openwork frame secured in the opening in said support, friction gripping means extending across the frame in spaced relation, resiliently-supported brushing means also extending across the frame alternating with the gripping means and being spaced therefrom, and scraping means also extending across the frame.

In testimony that I claim the foregoing as my invention, I have signed my name hereunder.

HERMAN E. GOTHLBERG.
